UNITED STATES PATENT OFFICE.

FRANKLIN D. CHILD, OF WEST NEWTON, MASSACHUSETTS.

COTTON-GIN.

SPECIFICATION forming part of Letters Patent No. 349,692, dated September 28, 1886.

Application filed April 3, 1886. Serial No. 197,632. (No model.)

To all whom it may concern:

Be it known that J. FRANKLIN D. CHILD, of West Newton, in the county of Middlesex and State of Massachusetts, have invented certain new and useful Improvements in Cotton-Gins, of which the following, taken in connection with the accompanying drawings, is a specification.

My invention relates to the class of cotton-gins known as "roller-gins;" and it consists in certain novel features of construction, arrangement, and combination of parts, which will be readily understood by reference to the description of the drawings and to the claims 15 to be hereinafter given.

Figure 1 of the drawings is a plan of a machine embodying my invention, one-half of each of two upper cross-bars being broken away to show the parts beneath. Fig. 2 is a 20 vertical section on line $\alpha\alpha$ on Fig. 1. Fig. 3 is an end elevation. Fig. 4 is a vertical section of a portion of the upper part of the machine on the same line as Fig. 2, but drawn to an enlarged scale. Fig. 5 is a plan of one of 25 the plate pressing-levers and portions of the beater-cylinder and seed-arresting plate, also enlarged; and Fig. 6 is a rear elevation of a portion of the pin-carrying bar and an attached cap.

In the drawings, A A are the side frames of 30 the machine, connected together by the bars B C, the feed-table D, and the plates E and F, said frames being slotted from their upper sides to receive the boxes a, b, and c.

G is the ginning-cylinder, having its periphery covered with leather d, and mounted in bearings in the boxes b b, (shown only by dotted lines in Figs. 2, 3, and 4,) said cylinder being arranged with its upper surface slightly 40 above the upper surface of the feed-table D, and having a rotary motion imparted thereto in the direction indicated by the arrow 1 on Figs. 3 and 4, by means of the belt I, leading from a pulley on the driving-shaft J to the pulley I' on the shaft of said cylinder.

Above the cylinder G, and mounted in the boxes a a, is the beater-cylinder K, provided with a series of oblique disks, e e, arranged with their peripheries in contact with or in 50 close proximity to the periphery of the cylinder G, said cylinder K being revolved in the

direction indicated by the arrow 2 on Figs. 3 and 4 by means of the crossed belt L, leading from the pulley L' on the driving-shaft to the pulley on the shaft of said cylinder K, as shown. 55 A thin metal breast-plate, f, having its under side curved transversely and its upper side beveled toward one edge, rests upon the periphery of the cylinder G, with its beveled edge toward the feed-table, but a short distance to 60 the rear of a vertical plane extending longitudinally through the axes of said cylinders G and K, said breast-plate extending the whole length of the cylinder G and being held in position thereon by the pad-like forward ends of 65 a series of levers, M, each pivoted to the under side of the bar B, and having pivoted to its rear end the bolt N, which extends upward through an open slot, g, formed in the rear edge of the bar B, and has fitted thereon the 70 spring h, washer h', and adjusting-nut h², as shown in Figs. 1, 2, and 4.

Each of the levers M has formed in the under side of the pad, at its front end, a shoulder, i, which abuts against the rear edge of the 75 breast-plate f, to prevent said plate being moved to the rear and downward by the revolution of the cylinder G.

The bar C is preferably cast in one piece with the caps C', and has set in its under side 80 a series of downwardly-projecting pins, i', as shown in Figs. 4 and 6, which, while they will permit the cotton-seed to pass them as they are thrown out over the breast-plate f and the pads of the levers M, so that they will fall up- 85 on the inclined plate E, and thence to the floor outside of the plate F, will serve to arrest any fiber which may be carried over the breast-plate f, and cause it to be carried around with the cylinder K and united with the cotton be- 90 ing fed to the ginning-cylinders.

A shaft, O, is mounted in bearings in the boxes c c, and has secured thereon two or more hubs provided with a plurality of radiating-arms, the extremities of which are connected 95 together by the longitudinal bars or plates j j, arranged to serve as strippers, to clean any fiber from the cylinder G that may adhere thereto after it has passed the breast-plate f, and cause it to fall upon the floor inside of the 100 plate F, a rotary motion, in the direction indicated by the arrow 3 on Fig. 3, being imparted

to said shaft and bars by means of the belt P, leading from the pulley P' on the driving-shaft to the pulley P² on said shaft O.

The boxes c c rest on the bottoms of the slots 5 formed in the frames A A, and the boxes b b rest upon the boxes c c, while the boxes a a are adjustable up and down in said slots by means of the set-screws k k, which work in threaded holes in the boxes a a after passing through 10 smooth holes in the caps C', and rest at their lower ends upon the boxes b b, as shown in Fig. 4, whereby the cylinder K may be adjusted toward or from the cylinder G.

The bar B is secured to the frames A at each 15 end by the bolts l, which pass through slotted holes in said bar and are screwed into said frames, so that said bar may be adjusted toward or from the cylinder K by means of said bolts and slots, and the set-screws m, for the 20 purpose of properly locating the breast-plate f.

By the use of the series of independently-movable levers M, arranged to press upon the breast-plate f, one portion of the plate f may rise to permit the passage of a bunch of fiber, 25 while other portions are held down by the levers not immediately affected by the passage of said bunch, it being understood that said breast-plate f is made sufficiently thin to permit it to spring under such circumstances.

30 What I claim as new, and desire to secure by Letters Patent of the United States, is—

1. In a cotton-gin, the combination of the ginning-cylinder, the breast-plate, and the series of spring-pressed levers, each provided 35 with a shoulder to abut against the rear edge of said plate, all constructed, arranged, and adapted to operate substantially as and for the purpose described.

2. The combination, in a cotton-gin, of a 40 ginning-cylinder, a breast-plate, a series of pivoted levers, each provided with a shoulder to abut against the rear edge of said plate, and a pad to rest upon said plate, a bolt pivoted to

each of said levers and provided with a nut, a washer, and a spring, and a bar provided in 45 one edge thereof with a series of open slots to receive said bolts, substantially as described.

3. The combination, in a cotton-gin, of a ginning-cylinder, a breast-plate, a series of spring-pressed levers, each provided with a 50 shoulder to abut against the rear edge of said plate, and a pad to rest upon the upper side of said plate, and a beater-cylinder provided with a series of obliquely-arranged disks, substantially as and for the purpose described. 55

4. The combination of the ginning-cylinder G, the plate f, the series of levers M, each provided with a nut, a washer, and a spring, the slotted bar B, the beater-cylinder K, and the bar C, provided with the series of fingers or pins 60 i, all constructed, arranged, and adapted to operate substantially as described.

5. The combination of the cylinders G K, the boxes a a b b, the caps C', and the set-screws k k, substantially as described. 65

6. In a cotton-gin, the combination of the ginning and beater cylinders, a plate, an adjustable bar provided with a series of open slots, a series of levers pivoted to said bar, and each provided with a shoulder to abut against 70 the rear edge of said plate, and a pad to press upon the upper side thereof, a bolt pivoted to each of said levers and arranged to engage with the slots in said bar, a nut fitted to the upper end of each of said bolts, so as to be 75 adjustable thereon, and a washer, and a spring mounted upon each of said bolts between its nut and said bar, substantially as described.

In testimony whereof I have signed my name to this specification, in the presence of two subscribing witnesses, on this 2d day of April, A. 80 D. 1886.

FRANKLIN D. CHILD.
